UNITED STATES PATENT OFFICE.

FRANK F. KIRCHNER, OF FULDA, MINNESOTA.

TIRE-FASTENING MEANS.

1,119,172.

Specification of Letters Patent.

Patented Dec. 1, 1914.

Application filed June 14, 1912. Serial No. 703,722.

To all whom it may concern:

Be it known that I, FRANK F. KIRCHNER, a citizen of the United States, residing at Fulda, in the county of Murray and State 5 of Minnesota, have invented a new and useful Tire-Fastening Means, of which the following is a specification.

One object of the present invention is to provide novel means for holding the longitudinal edges of a tire interlocked with a 10 rim.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the 15 scope of what is claimed without departing from the spirit of the invention.

In the accompanying drawings.—Figure 1 shows in sectional side elevation, a portion of a wheel equipped with the device 25 constituting the subject-matter of this application; Fig. 2 is a transverse section of the structure shown in Fig. 1, the cutting plane being passed along the line A—B of Fig. 1; Fig. 3 is a perspective of one of the 30 tire sections; Fig. 4 is a perspective of the tire-retaining member.

In the drawings there is shown a rim, denoted generally by the numeral 1, the same comprising a felly 2 and a felly band 3, the felly band 3 having clencher ribs 4. The tire is preferably fashioned from resilient metal and comprises a plurality of trough sections 5 having at their ends, projecting tongues 6. Considering each section 5 as 40 a unit, the tongues which are upon the opposite ends of each section alternate with each other circumferentially of the tire. When one section 5 is assembled with another like section, the tongues of the adjacent sections will alternate with each other circumferentially of the tire, the tongues of each section extending beneath the body portion of the next adjoining section. Owing to this construction, the desired play 45 of the meeting ends of the sections 5 will be afforded, and at the same time, the tire will be of great strength at the meeting ends of the sections. The sections 5 are equipped at 50 their edges with clencher flanges 7 which

engage with the clencher ribs 4 of the felly 55 band 3.

The invention further includes a pair of tire-engaging members 8 which may be severed rings, resting upon the felly band 3, the members 8 having inclined outer faces 9 60 adapted to engage the sections 5 to hold the flanges 7 engaged with the clencher ribs 4. The inner faces of the tire-engaging members 8 slant toward the median plane of the wheel and toward the hub of the wheel, as 65 indicated at 10.

The invention further includes a plurality of tire-retaining members 11, of which tire-retaining members there may be any number. The tire-retaining member 11 is 70 preferably in the form of a plate provided at its edges with diverging flanges 12 adapted to engage the faces 10 of the tire-engaging members 8.

Extended through the tire-retaining member 11, and if desired, rigidly connected therewith, is a bolt 14 which passes through the felly band 3 and through the felly 2, there being a nut 15 upon the bolt 14, which nut engages the intrados of the felly 2. 80 Pins 17 or other projections extend from the felly band 3, the pins 17 engaging in slots 16 formed in the body portion of the tire-retaining member and extended through the flanges 12 thereof. 85

Presupposing that the parts are positioned as shown in Fig. 2 it will be observed that by loosening the nut 15, the bolt 14 may be moved toward the periphery of the tire, carrying with it the tire-retaining member 11, the hold of the tire-retaining member 11 upon the tire-engaging members 8 being broken, whereupon the tire-engaging members 8 may be moved toward each other, and toward the median plane of the wheel, so as 90 to permit the clencher flanges 7 of any desired section 5 to be disengaged from the clencher ribs 4 of the felly band 3, whereupon any desired section 5 may be disengaged from the adjoining sections, to permit the renewal of a 100 defective section. The manner in which the tongues 6 of the sections interengage with each other has been pointed out hereinbefore. The projections 17 serve to prevent the tire-engaging members 8 from moving 105 too far in the direction of the median plane of the tire when the tire-retaining member 11 is loosened. In addition to the foregoing

function, the projections 17 engage the tire-retaining member when the same is seated on the felly band 3, and serve to prevent the tire-retaining member 11 from moving circumferentially of the wheel.

As will be understood readily, when the nut 16 is tightened, the flanges 12 of the tire-retaining member 11 will engage with the faces 10 of the tire-engaging members 8, forcing the members 8 laterally until their faces 9 engage with the sections 5 and force the flanges 7 into engagement with the ribs 4.

Recalling that the sections 5 are fashioned from spring metal, it is obvious that the wheel will possess the desired resiliency, and at the same time, the possibility of a puncture will be avoided. The sections 5 may be provided with any suitable gripping and anti-skidding means, indicated generally at 18.

Having thus described the invention, what is claimed is:—

In a device of the class described, a rim

having ribs; tire engaging bands on the rim; 25 a tire having its edges interlocked with the ribs and located between the ribs and the bands; a tire retaining strip bearing against the inner edges of the bands to hold the latter in contact with the tire; and a securing 30 element uniting the strip with the rim; the strip having elongated transverse openings and the rim having pins which engage in the openings to hold the strip against creeping, the strip being removable from the pins and the pins lying between the securing element and ribs and in the path of the bands, thereby to limit the movement of the latter toward the median plane of the rim when the strip is removed from the pins. 35

In testimony that I claim the foregoing as my own, I have hereto affixed my signature in the presence of two witnesses.

FRANK F. KIRCHNER.
